LOCK AND SWITCH DEVICE

Robert Macdonald, Chicago, Ill.

Application June 20, 1934, Serial No. 731,548

3 Claims. (Cl. 200—44)

This invention relates to lock and switch devices and is particularly concerned with novel and improved locks and switches in which are incorporated novel features applicable to a variety of devices of this general class.

The invention herein disclosed may be considered a division, in part, of my copending application, Serial No. 658,978, filed February 28, 1933 and matured into Patent No. 2,057,532, issued October 18, 1936. In this patent I have shown and described a novel key or operating member, for locks and switching devices, comprising a shell in which is disposed a bit made of insulating material. This bit may be provided with grooves and notches according to known devices of this character, or it may represent the replica of at least part of a finger print. If the bit of the key carries such a finger print, it will represent not only an operating member in the ordinary and known sense but an operating member which carries individual identification marks. In the bit are disposed conductors forming contacts on the surface thereof, that is to say, forming contacts along its serrated portion. The lock or switching device to be operated by such a key or actuating member carries a serrated portion or ward made of insulating material and representing the counterpart of the bit. In other words, the bit of the key and the ward of the lock are each provided with an insulating member on which are disposed grooves or serrations corresponding either to any known and desired scheme or representing characteristic lines taken from a finger print. Conductors are also disposed in the ward portion of the switch or lock, forming contacts along the serrated portion thereof and adapted to form a circuit with the contacts and conductors on the bit of the key or actuating member. The circuit is completed when the serrated portion of the key meshes with or engages the serrated portion of the ward for the purpose of actuating electric mechanisms to perform the locking, unlocking or other switching functions, depending on the purpose for which the device is intended.

It may be mentioned at this point that I use the terms "bit" and "ward" in the broadest sense to designate the serrated portions on the operating member and on the corresponding member, respectively, which is disposed in the device. The terms "key" and "lock" or equivalents thereof are likewise used merely for the sake of convenient description. I have adopted these terms from the terminology of locks but, it is understood, that the invention is not in any way

limited to keys and locks. It is applicable to a great variety of switching devices used in widely different fields.

In addition to the operating circuit previously mentioned above which is closed when the serrated portion of the key is brought into engagement with the serrated portion of the ward, I have provided a safety or hazard circuit which is actuated in case of tampering with the device. This hazard circuit comprises conductors disposed within the ward portion in the device and also forming contacts on the serrated portion thereof. The conductors corresponding to the hazard contacts on the ward are wired to a signal or control circuit in which may be included an alarm, if desired. This circuit is closed at such time when a wrong key or operating member is inserted or in case of any tampering with the device. An electro-magnetic device included in the hazard circuit is actuated and initiates the necessary signalling and control operations.

The following description and appended claims are chiefly directed to the features referring to the switching and locking device as disclosed in the above mentioned prior case and are also directed to improvements on these features.

The invention will be described with reference to the accompanying drawing in which

Fig. 1 shows one embodiment of a key or actuating member having on one of its sides a serrated portion representing the bit;

Fig. 2 is a longitudinal cross section thru an embodiment of a complete switching device; and

Fig. 3 is a transverse cross section thru the device shown in Fig. 2, substantially along the lines 3—3 and looking in the direction of the arrows.

Referring now to Fig. 1, the operating member shown in this figure comprises a shell or housing designated by reference numeral 11. At one end of this shell is a handle portion 12 which may be formed somewhat like the usual handle portion on an ordinary key. The edge 13 of this operating member may be rounded. Enclosed in the shell 11 is an insulating member 14 having a uniform or sectional grooved or serrated face as shown. The serrations may be in accordance with a specific finger print, that is, characteristic lines may be taken from a finger print and provided on the face of the insulating member 14 as indicated. Any other design or scheme may be used in place of the finger print. This insulating member contains conductors forming contacts on the face of the serrated portion as is indicated in the drawing by the reference numeral 55

15. Certain ones of these contacts may be blind, that is, may be merely contact points without serving any particular function in the circuit operations which I will presently describe, while 5 certain other contacts are parts of or connected with the aforementioned conductors contained within the bit or enclosed thereby.

The above described switching means or key is particularly suitable in case of a device where 10 the key is inserted and rotated in order to effect engagement of its grooved portion with the grooved face of a control member enclosed within the device. The key may also take the form of a member that is simply pushed into the lock and 15 the required engagement with the internally disposed control member is effected either mechanically or electrically by moving the entire key against the enclosed control member, as described in the prior case.

20 In Figs. 2 and 3 is shown a switching device incorporating the features previously indicated, with additional features appearing from the following detailed explanation. This device uses a key as noted above, that is, one which slides into 25 the corresponding aperture of the device, its actuation depending upon electrical features described below.

The key 90 shown in Fig. 2 consists of a flat shell containing the bit 91. However, whereas 30 the bit shown in the previous disclosure was fixed in the shell of the key, the bit member 91 shown in Fig. 2 is longitudinally movable within the shell of the key. A spring 92 at one end of the bit and a spring 93 at the other end thereof 35 exert a pressure on the corresponding ends of the bit member 91, holding the bit member in a predetermined neutral position. A groove 94 may be provided on the enclosed side of the bit 91 for receiving a projection 95 rising from the 40 material of the shell of the key or provided thereon. The bit is thus longitudinally movable within the shell of the key and the limits of movement depend on the springs 92-93 and to some extent on the cooperation of the projection 95 with the notch 94. The projection 95 tends to align the bit properly within the shell 45 of the key. It is understood, of course, that other aligning means may be employed in place of those which I have shown. At the forward end of the 50 key 90 is provided an insulating member 96 carrying a contact 97.

Since the other important component parts of the device are already known from the prior case, I will limit the following explanation chiefly 55 to the functions of this embodiment.

When the key 90 is pushed into the key guide 98, it will finally come to a stop at the moment when the contact 97 engages a pair of contacts 99. These contacts are wired to the conductors 100-101. A circuit is now closed from the battery 102 over the wires 100-101 to the windings of the solenoids 103 and 104 and back to the battery 102 by way of conductors 105-106. The solenoids attract their plungers or armatures and the key guide 98 is lifted upwardly 60 until the serrated portion of the bit of the operating member 90 is in engagement with the serrated portion of the ward 107. A circuit is now closed over the conductors 108-109 and contact 70 10' for the energization of the electro-magnet 111. It may be remarked at this point that the contact 97 at the end of the key 90, which initially 75 closes the circuit for the operation of the solenoids 103-104 is large enough so that the connection and the resulting circuit is maintained

in spite of the attraction of the key guide and key into engagement with the ward. The solenoids 103-104 remain energized. Hazard conductors and contacts corresponding thereto are also provided in the ward 107. These hazard conductors may be grouped in any desired manner and the resulting groups may be connected to the alarm conductors 112-113. In case a circuit is closed either from ground over any of the points connected to the conductor 113 or over 10 any pair of contacts of any group of wires connected to conductors 112-113, the signal device or relay 110 energizes in circuit with the alarm 114, and thereby actuates the contact 110' to open the operating circuit in addition to initiating the 15 required signaling operations.

Assuming now that the key 90 is to be withdrawn from the device, a pull will be exerted on the key and this pull will first effect the spring 92 which aligns the bit 91 of the key housing. 20 The bit itself remains in engagement with the ward 107. The spring 92 is compressed, that is, the shell of the key slides to the right while the bit remains in engagement with the ward. The circuit of the solenoids 103-104 is now broken 25 at the contacts 97-99. The solenoids de-energize and drop the key guide 98. The key assumes the position shown in the drawing and can now be completely withdrawn.

Changes and modifications may be carried out 30 within the scope and spirit of the following claims in which I have defined what I believe is new in the art.

I claim as my invention:

1. A lock and switch device of the class described comprising, an enclosed substantially stationary control member, a removable key carrying a movable companion control member, means for guiding said key into said device to position said movable control member of said key opposite 40 said enclosed stationary control member but spaced therefrom, electromagnetic means, contact means on said key for energizing said electromagnetic means upon insertion of said key whereby said key is moved to position the control member thereof in engagement with said enclosed stationary control member and to maintain the engagement therebetween, said movable companion control member of said key remaining initially in engagement with said stationary enclosed control member upon withdrawal of said key from said device, whereby said electromagnetic means is first deenergized to release the engagement between said control members prior to full withdrawal of said key from said device. 55

2. In a lock and switch device, an enclosed stationary grooved control member, a removable key for operating said device, a movable grooved companion control member on said key, electromagnetic operating means, means on said key for energizing said operating means upon full insertion of said key in said device whereby said key is moved against said stationary control member to effect engagement of the movable grooved control member thereon with said grooved stationary control member to actuate said device, said grooved control members remaining in engagement upon partial withdrawal of said key until said electromagnetic means is deenergized by said partial withdrawal of said key whereby 65 the engagement of said grooved members is broken.

3. The structure defined in claim 2, wherein said key comprises a metallic shell having an opening, an insulating body contained in said 75

shell and carrying a grooved face disposed in said opening, said insulating body constituting said movable grooved companion control member, resilient means for centering said insulating body with respect to said opening and said shell, said insulating body being movable against said resilient

means with respect to said shell, and contact means at the end of said key constituting said means on said key for energizing said operating means upon full insertion of said key in said device.

5

ROBERT MACDONALD.
